Inventor:

Lewis W. Harris;

Robert H. Randle,
Attorney.

UNITED STATES PATENT OFFICE.

LEWIS W. HARRIS, OF RICHMOND, INDIANA.

RAILWAY-RAIL LOCK.

1,407,999.

Specification of Letters Patent. Patented Feb. 28, 1922.

Application filed December 28, 1921. Serial No. 525,286.

To all whom it may concern:

Be it known that I, LEWIS W. HARRIS, a citizen of the United States, residing in the city of Richmond, in the county of Wayne, 5 State of Indiana, have invented a new and useful Construction in Railway-Rail Locks, of which the following is a full, clear, and comprehensive specification and exposition, the same being such as will enable others to 10 make and use the same with exactitude.

The object of my present invention, broadly speaking, is to provide a railway rail lock which is strong and durable in construction, positive in action, simple in character, mechanically efficient in operation, 15 easily placed in active position, and which can be manufactured and sold at a comparatively low price.

It is a well known fact that the ordinary 20 railway spikes which are driven into wooden ties soon become loose in the wood and therefore lose their grip upon the rails which they are expected to hold in place. The loosening of the spikes usually necessitates a new tie in which the spike will hold, 25 thereby causing a great loss both in as to the tie per se and in the replacement thereof. Therefore the principal object of this invention is to overcome the above mentioned objections and thereby prolong the usefulness 30 of the tie, and more particularly making transportation thereover more safe and secured.

Other minor objects and particular objects will suggest themselves in the course 35 of the following description.

The preferred means for carrying out the principles of my invention in a practical manner is shown in the accompanying drawings, in which—

Figure 1 is a perspective view of a portion of a railway rail and tie, and showing my invention in operative condition in connection therewith. Figure 2 is a front elevation 45 of the stem or body of my construction, showing the bolt and nut in connection therewith, but with the dog and the washer omitted therefrom. Figure 3 shows a cross section of a portion of a tie, showing one of my devices in elevation and another in central vertical section, and Figure 4 is a cross section, as taken on the line 4—4 of Fig. 2.

Similar indices denote like parts throughout the several views.

In order that the construction, the opera-

tion, and the advantages of my invention may be more fully understood and appreciated, I will now take up a detailed description in which I will set forth the several 60 features as fully and as clearly as I may.

In the drawings letter A denotes an ordinary railway rail, and B denotes a wooden railway tie on which the rail rests.

Usually the rail and the tie are secured 65 together by means of ordinary railway spikes (not shown).

My invention comprises a metal body 1, which is substantially square in cross section, and about the dimension and shape of 70 a railway spike. Said body has its lower rear corner truncated or beveled whereby the lower end of the body terminates in the edge-like end 2. The head 3 of the body has a threaded aperture formed centrally there- 75 through and extending longitudinally of the body to receive the tap bolt 4 therein.

The front side of the body 1, below the head 3 is hollowed out forming a channel which tapers downward from the head 3 to 80 the point 2, and its shape and size are such as to neatly receive therein the wedge 5, as shown in Figs. 2, 3 and 4.

When the upper end of the wedge 5 is in contact with the lower face of the head 3 85 then the wedge will be nested entirely within the body, as shown in the drawings. Should the bolt 4 be run down it is evident that it will contact with the upper end of the wedge and force it downward and outward, for the 90 purpose hereinafter appearing.

Numerical 6 denotes a dog having a lip 7 which is applied to fit over the edge of the base of the rail A, and there is a smooth bore aperture formed through the dog in 95 which may loosely operate the threaded portion of the bolt 4.

Extending upward from each of the two sides of the head 3 are the ears 8, between which the dog 6 is located when in operation 100 and by which the dog 6 is prevented from turning on the bolt.

Threaded on the bolt 4 is the nut 9. Located on the bolt 4 and below the nut 9, and above the dog 6, is the locking washer 10.

In practice the device is assembled by placing the nut, the washer, and the dog on the bolt 4, as in Fig. 2. The bolt is then inserted into the threaded aperture of the head but it should not at this time be extended therethrough. The wedge 5 is next 110 placed in the channel of the body as shown.

The ordinary spike should be withdrawn from the tie and the point 2 of my device is first entered into the aperture left by the spike, after which the device should be 5 pressed down until the top of the head 3 is substantially even with the surface of the tie, with the lip 7 of the dog resting on the base of the rail. The nut 9 should now be held from turning and at the same time the 10 bolt 4 should be turned to drive it downward, its lower end engaging the wedge 5 and driving the wedge downward and of course outward or forward which, manifestly, will tighten the device in the spike 15 aperture, after which the nut 9 should be run down to tightly clamp the washer 10 upon the top of the dog 6, and thereby causing the lip 7 of the dog to tightly engage the base of the rail. With one of my devices 20 on each side of the rail, as in Fig. 3, it is evident that the rail will be securely held in place, thereby accomplishing the objects of this invention.

It is to be understood that various changes 25 may be made in the several details of construction herein set forth without departing from the spirit of the invention and without sacrificing any of the advantages thereof which are new and useful.

30 Having now fully shown and described my invention, what I claim and desire to secure by Letters Patent of the United States, is—

35 1. A railway rail lock comprising a body portion adapted to be inserted into an aper-

ture in a wooden tie from which an ordinary spike has been withdrawn, a wedge contained in said body, a tap bolt extending up from the body and adapted to run down into engagement with the wedge to drive the 40 wedge downward and outward, a dog above the body with said bolt extending therethrough, a nut on the bolt to clamp the dog into engagement with the base of a rail, all substantially as shown and described. 45

2. A railway rail lock comprising a pointed body, a tapered wedge located in said body and adapted when forced downward to project outward from the side of the body, a bolt for driving said wedge downward, a 50 dog loosely mounted on said bolt, a nut threaded on the bolt for causing said dog to clamp the base of a railway rail, all substantially as shown and described.

3. A railway rail lock, comprising a body 55 which is substantially square in cross section with one of its lower corners truncated and having a hollow interior whose base is disposed at an angle, a taper wedge fitting in said body, a bolt threaded in an axial direction through the upper portion of the body and adapted to engage said wedge, a nut threaded on the bolt above said body, a locking washer below said nut, a dog through which said bolt may freely pass and located 60 between the washer and the upper end of the body, and means for preventing said dog from turning on the bolt, all substantially as shown and described. 65

LEWIS W. HARRIS.
